Attorney

UNITED STATES PATENT OFFICE.

GEORGES CLOETENS, OF BRUSSELS, BELGIUM, ASSIGNOR OF ONE-THIRD TO GEORGES LALOUX, OF LIEGE, BELGIUM, AND ONE-THIRD TO LOUIS VAN DER HEYDEN A HAUZEUR, OF BRUSSELS, BELGIUM.

PIANISSIMO DEVICE OF THE CURTAIN TYPE.

1,392,247.

Specification of Letters Patent. Patented Sept. 27, 1921.

Original application filed January 19, 1920, Serial No. 352,345. Divided and this application filed March 7, 1921. Serial No. 450,498.

To all whom it may concern:

Be it known that I, GEORGES CLOETENS, manufacturer of organs at Brussels, Belgium, 37 Rue de Lauzanne, a subject of the 5 King of Belgium, have invented certain new and useful Improvements in Pianissimo Devices of the Curtain Type; and I do hereby declare the following to be a full, clear, and exact description of the invention, such as 10 will enable others skilled in the art to which it appertains to make and use the same, reference being had to the accompanying drawings, and to letters or figures of reference marked therein, which form a part of this 15 specification.

This invention relates to a pianissimo device of the curtain type, being a division of an application entitled "Stringed musical instruments", filed Jan. 19, 1920, Serial No. 20 352,345.

The object of the invention is to provide apparatus for use in connection with stringed instrument played by hammers for interposing a band of felt, leather, woven 25 fabric, or other flexible material, between the strings and the hammers for softening the sounds produced by the strings.

The above result is attained according to the present invention by providing supporting means for the flexible band so arranged 30 with respect to the musical instrument with which it is associated that the band may be inserted between the strings and hammers by a movement at right angles to the strings 35 and in a plane substantially parallel to the plane of the strings whereby all or a portion only of the strings may be affected.

In the accompanying drawings, which show, by way of example, some constructional forms of the invention,—

Figure 1 is a partly diagrammatic view of the general arrangement of the strings of a piano and of the apparatus according to one embodiment of the invention.

Fig. 2 is a perspective view, on a larger scale, of a portion of the pianissimo device illustrated in Fig. 1.

Fig. 3 is a side elevation of a modified form of pianissimo device.

The strings 3 are stretched in the usual way over the plate 1, 2. They are operated

in the usual way by hammers (not shown) acting at a certain distance from the front part 1 of the plate.

The apparatus for softening the sounds of the strings comprises, in the constructional form of the invention illustrated in Figs. 1 and 2, two bands 4 of felt, leather, textile fabric or other flexible material, passing over terminal reels 5 and supported by two firmly 55 stretched ribbons 6 in such manner that the bands 4 can remain slack when they are inserted between the hammers and strings. The blow of the hammer is then transmitted to each string through the band 4 so that the 60 sound is softened.

Each reel 5 is provided with a spiral spring 7 and a ratchet wheel 8 with which a pawl 9 co-operates. To the free end of each band 4 is attached a rod 10 by means of 70 which the band may be moved and which at the same time acts as an indicator of the position of the band. As the band 4 is unwound off the reel in moving it between the hammers and strings, spring 7 is wound up 75 and the pawl 9, under the influence of its spring 11, engages the ratchet 8 and prevents rewinding of the band on the reel. When the pawl is disengaged from the ratchet, the spring 7 turns the reel in the 80 direction to withdraw the band from between the hammers and strings and rewind it on the reel.

Fig. 3 shows a somewhat simpler construction of pianissimo device than that 85 shown in Figs. 1 and 2. In this form of the invention four guide pulleys 5' are provided, two at each side of the plate 1, 2. A band 4' of felt or the like extends over the pulleys 5' and has its ends connected by 90 cords or ribbons so as to form an endless strip. One of the pulleys 5' is provided with a handle 12.

It will be obvious that with the construction shown in Figs. 1 and 2 it is possible to 95 soften the sounds of all or any number of the strings by moving either or both of the right and left-hand bands 4 between any desired number of strings and hammers. With the construction shown in Fig. 3 the band 4' 100 may be moved from either the right-hand side of the piano or from the left-hand side

thereof between any desired number of strings and hammers by turning the handle 12 in the desired direction.

Having now particularly described my invention in certain of its embodiments what I claim is:—

1. A stringed musical instrument played by hammers, and having a band of felt or the like supported in proximity to a side of the instrument for insertion between the strings and the hammers by a movement at right angles to the strings and in a plane substantially parallel to the plane of the strings.
2. In a stringed instrument played by hammers, two bands of felt or the like mounted to be inserted at the will of the player between the strings and the hammers, guiding ribbons stretched transversely between the hammers and the strings over the whole width of the instrument for supporting said bands, and guiding reels at each side of the instrument for said bands.

3. In a stringed instrument played by hammers, two guiding ribbons stretched transversely between the hammers and the strings, a reel at each side of the instrument, a band of felt or the like wound upon each reel, a handle at the free end of each band, a spring producing the winding up of each reel, a ratchet on each reel and a pawl engaging said ratchet and adapted to lock the reel against the action of its spring.

4. In a stringed instrument played by hammers, two guiding ribbons stretched transversely between the hammers and the strings, reels at the ends of said ribbons and under the instrument, and bands of felt or the like led on said ribbons and reels.

In testimony whereof I affix my signature in presence of two witnesses.

GEORGES CLOETENS.
